Des. 229,167
Patented Nov. 13, 1973

229,167

PRICE TAG HOLDER

Peter De Korte and Henry Hopper, Wyckoff, N.J., assignors to Empro Products Company, Inc., Paterson, N.J.

Filed Dec. 28, 1971, Ser. No. 213,229

Term of patent 14 years

Int. Cl. D8—08

U.S. Cl. D8—245

Fig. 1.

Fig. 2.

Fig. 3.

Fig. 4.Fig. 5. *Fig. 6.*FIG. 1 is a front elevation of a price tag holder, showing our new design;

FIG. 2 is a bottom plan view thereof;

FIG. 3 is a rear elevation thereof;

FIG. 4 is a cross sectional view through the holder on the line 4—4 in FIG. 1;

FIG. 5 is another front elevation thereof; and

FIG. 6 is a side elevation thereof.

The broken line representations of price indicia cards in FIGS. 1 and 5 are for purpose of illustration only.

We claim:

The ornamental design for a price tag holder, substantially as shown and described.
